UNITED STATES PATENT OFFICE.

BENJAMIN F. STAUBER, OF CHICAGO, ILLINOIS, ASSIGNOR TO GABE FELSENTHAL, OF SAME PLACE.

DESIGN FOR A FRAME FOR LOOKING-GLASSES.

SPECIFICATION forming part of Design No. 28,616, dated May 10, 1898.

Application filed January 22, 1898. Serial No. 667,654. Term of patent 7 years.

To all whom it may concern:

Be it known that I, BENJAMIN F. STAUBER, a citizen of the United States, residing at Chicago, in the county of Cook and State of Illinois, have invented and produced a new and original Design in Frames for Looking-Glasses, Pictures, Advertising-Signs, and the Like, reference being had to the accompanying drawing, forming a part hereof.

In the accompanying drawing the figure is a perspective view of my design.

The leading feature of my design consists principally in the base portion, extending to the front and rear and joined together, and upright side portions joined together, all arranged so as to present a skeleton outline.

A A are the base or leg portions, joined to-

gether at a. B B are upright side portions joined together at the top at b, the whole presenting to the eye a harmonious and ornate figure, as shown in the accompanying drawing.

In the drawing the upright side portions B are provided with two spheres C C and a wire portion D, as shown, connecting the same.

I claim—

The design for a frame for looking-glasses or similar articles, substantially as shown and described.

BENJAMIN F. STAUBER.
